UNITED STATES PATENT OFFICE.

HENRY G. CORDLEY, OF GLENRIDGE, NEW JERSEY.

WATER-COOLER.

No. 903,844.

Specification of Letters Patent. Patented Nov. 17, 1908.

Application filed June 8, 1905. Serial No. 264,277.

To all whom it may concern:

Be it known that I, HENRY G. CORDLEY, a citizen of the United States, residing at Glenridge, in the county of Essex, State of New Jersey, have invented certain new and useful Improvements in Water-Coolers, of which the following is a description, reference being had to the accompanying drawing, and to the letters and figures of reference marked thereon.

My invention relates to water coolers, particularly to that class of water coolers in which the water to be cooled is kept separate from the ice used for cooling it and in which the water to be cooled is supplied from a bottle. A large demand has arisen in recent years for purer drinking water than that supplied by the water systems of most cities and this demand has been met by the sale of spring or other pure water in glass bottles. For convenience in handling, these bottles are usually of half gallon size though larger bottles are also used. It is generally considered desirable to cool this water for drinking purposes and to do so without permitting it to come in contact with the ice, and a number of coolers have been invented designed for cooling the water from large sized bottles, but such devices have not usually been adapted to receive and be supplied from the half-gallon bottles.

It is the purpose of the present invention to provide a simple and inexpensive construction of cooler, particularly adapted to receive and be supplied from half-gallon bottles, though adapted also for use with larger bottles, and with this purpose in view my invention consists in the construction and combination of elements hereinafter described and particularly pointed out in the claims.

Referring to the drawings: Figure 1 is a vertical sectional view showing the complete device with a water bottle in position; Fig. 2 is a top plan view of the complete device and Fig. 3 is an enlarged sectional view showing the faucet.

In the drawings A is the outer casing for containing the ice and is preferably made of what is known as indurated fiber. Near its bottom the casing A is provided with a faucet B having discharge spout b outside the casing and adapted to be operated by pressing in the push piece b'. Within the casing the faucet is provided with an open-ended

socket b² preferably provided on its interior with a gasket b³ of rubber. The open end of the socket b² is upward. For convenience in securing the faucet in place, the 60 faucet is preferably made in two parts united by a screw joint b⁴ each part being provided with a flange b⁵.

The casing A is provided at its upper end with a cover C having at its edge a down-turned flange c and having a circular opening c' formed in it. The cover has also formed in it an opening c² provided with a lid c³.

Within the casing A is placed a jar D 70 open at its upper end and having extending downward from its bottom a nipple d preferably slightly tapered and adapted to fit the socket b² and to form with the gasket b³ a liquid tight joint.

The weight of the jar is supported by the faucet. The jar is of such height as to extend through the circular opening c' of the cover which is of such size as to receive and fit snugly about the upper end of the jar, 80 the cover thus being kept from movement by the engagement of its flange c with the upper edge of the casing, serving to hold the upper end of the jar in proper position. Within its upper end the jar is provided 85 with a groove d' in which is placed a gasket d² preferably of round rubber. The interior diameter of the jar is such as to permit the neck of a half gallon bottle of the usual form to enter it freely and to receive the 90 shoulder between the neck and body of the bottle upon its upper edge in contact with the gasket d².

The opening c' of the cover is placed to one side of the center so as to afford as much 95 room as possible for the opening c².

The jar D may be of any desired material but is preferably of earthenware. The cover C is preferably of sheet metal.

In use, the faucet being in place with the 100 socket b² upturned, the cover is put in place and the jar D is inserted through the opening c', and its nipple d inserted in the socket b². Broken ice may then be inserted through the opening c² of the cover and a bottle of water 105 is then placed in position as shown in Fig. 1 with its neck within the upper end of the jar D and with its shoulder resting on the gasket d². The water flows from the bottle filling the jar until its level reaches the end 110 of the bottle neck when it prevents entrance of air to the bottle thus stopping the flow of

water and serving as a seal. As water is drawn off through the faucet lowering the level of the liquid in the jar below the mouth of the bottle neck, air is permitted to enter 5 the bottle and the water flows out until the level of water in the jar is restored.

By utilizing the cover for holding the jar in position, I avoid the necessity for special means for this purpose and thus simplify and 10 cheapen the construction. The gasket at the upper end of the jar makes with the shoulder of the water bottle a sufficiently tight joint to prevent entrance of foreign matter while permitting entrance of sufficient air to allow of 15 flow of water from the bottle when the level of the water in the jar gets below the mouth of the bottle neck.

Any tendency of the bottle to tip over is prevented by contact of the mouth of the bottle 20 with the interior of the jar.

In case it is desired to clean the casing the jar D may be lifted out, the cover C lifted off and the contents of the casing may be readily emptied out by turning it over. All parts of 25 the device may thus be readily cleaned.

While I have described the construction as particularly adapted for use with half gallon bottles, I do not desire to be restricted to

its use with bottles of any particular size as it is evident that by properly proportioning the strength of the parts it may readily be adapted to be used with bottles of larger size.

Having thus described my invention, what I claim and desire to secure by Letters Patent is:—

In a water cooler the combination with an outer casing provided with an upwardly opening socket within the casing; a jar within the casing and supported by said socket and provided with a nipple adapted to enter the socket; a removable cover for the casing provided with a downwardly depending flange for engaging the casing adjacent the upper end thereof, and having an opening therein adapted to receive the upper end of the jar and to maintain it in position, the cover also being provided with an opening having a lid for the introduction of ice; a groove at the upper end of said jar; and a gasket located within the said groove. 5

In testimony whereof I affix my signature, in presence of two witnesses.

HENRY G. CORDLEY.
